UNITED STATES PATENT OFFICE.

DANIEL B. BADGER, OF WINCHESTER, AND ARTHUR C. BADGER, OF BOSTON, MASSACHUSETTS.

FIREPROOF WINDOW.

No. 821,975.

Specification of Letters Patent.

Patented May 29, 1908.

Application filed June 27, 1905. Serial No. 267 223.

To all whom it may concern:

Be it known that we, DANIEL B. BADGER, of Winchester, in the county of Middlesex, and ARTHUR C. BADGER, of Boston, in the county of Suffolk, State of Massachusetts, have invented certain new and useful Improvements in Fireproof Windows, of which the following is a specification.

This invention relates to sheet-metal fire-
10 proof windows and sashes of the type shown
and described in the Patent No. 651,096,
granted to us June 5, 1900, for fireproof win-
dow, and has for its object to improve cer-
tain details of construction of the window-
15 sash, making the same stronger and more
rigid.

For the details of the invention reference
may be had to the following specification
and drawings accompanying the same, in
20 which—

Figure 1 represents a front elevation,
partly broken away and in section, of a win-
dow constructed in accordance with our in-
vention, showing one side of the frame and
25 sashes of the window. Figs. 2 and 3 repre-
sent, respectively, a vertical section and a
horizontal section of the same, taken on lines
2 2 and 3 3 of Fig. 1. Figs. 4 and 5 repre-
sent detail perspective views of portions of
30 the top and bottom rails of the window-sash.
Fig. 6 represents a cross-section on line 6 6
of Fig. 1, showing the bottom sash in section.
Fig. 7 represents a section on line 7 7 of Fig. 2.
Fig. 8 represents a perspective view of the
35 plate by which is secured to the window-
frame the pulley over which passes the sash-
balancing chain. Fig. 9 represents a frag-
mentary elevation of the side rail of one of
the sashes. Fig. 10 represents a longitudinal
40 section taken through the cross-rail of the
sash, showing a different construction. Fig.
11 represents a cross-section on line 11 11 of
Fig. 10. Fig. 12 represents a fragmentary
perspective view of one end of the longitudi-
45 nal webs of this form of sash. Fig. 13 repre-
sents a similar view showing the same in
place in the sash. Fig. 14 represents a cross-
section on line 14 14 of Fig. 11.

The same reference characters indicate the
50 same parts in all the figures.

Referring to the drawings, 1 designates the
window-frame, and 2 and 3 the lower and up-
per sashes, respectively; both frame and
sashes being made of sheet metal bent into

form and the pane of the sash preferably com- 55
posed of wire-glass.

The sashes are composed of side rails 4,
constructed of a body-strip 5 of sheet metal,
having a groove for receiving the pane 7, and
an outer strip 8, connected at its edges to the 60
two edges of the body-strip 5, as shown in the
patent hereinbefore referred to, except that
the joint, instead of being made by doubling
the edge of the body-strip 5 back on itself and
then outwardly, is made by simply turning 65
back the edges of the body-strip once and
forming a double bend on the edges of the
outer strip to form interlocking lips, as shown
in Fig. 3. The top and bottom rails 16 17 of
the sashes are constructed substantially the 70
same as are the corresponding parts of the
patent referred to, as are also the rails 22, 23,
and 31 of the frame, for a fuller description
of which reference may be had to the said
patent. The essential features of the pres- 75
ent invention consist in the construction of
the cross-rails 10 of the sashes and in the
means by which said cross-rails are rigidly
and securely as well as detachably connected
to the exterior rails forming the frames of the 80
sashes. Each cross-rail 10 is constructed of
two strips 11 11, which are located side by
side with their edges in contact, such edges
being each folded back upon itself, so as to
form lips or guides 12 13, which are engaged 85
and locked together, this forming a construc-
tion in which the edges of the strips are folded
together and interlocked. The intermediate
portions of the strips are bent outwardly
from the folds and separated from each other, 90
being bent sharply inward or indented longi-
tudinally at their central portions to form
grooves 14 for receiving the panes 7, the in-
wardly-bent portions of the strips forming
also, in the interior of the rail, ridges 15, which 95
separate the interior of the rail into two lon-
gitudinal passages 18 19. Within the cross-
rail located between the ribs 15 and extend-
ing across from one edge to the other of the
strips, its edges being in contact with the 100
folded portions 12 13, is a plate or web 20,
which runs longitudinally of the rail almost
from one end to the other and serves to stiffen
the same and retain it in shape.

The cross-rail is detachably and firmly con- 105
nected to the top and bottom rails 16 17 by
means of projecting members or tongues 21
24, arranged in pairs side by side and project-

- from the top and bottom rails, respectively. These tongues are shaped in cross-section to correspond with the passages 18 19, being separated from each other by a distance equal 5 to the width of the ribs 15, so that they are adapted to extend into the ends of the cross-rail and fit closely therein. The tongues 24 are rigidly connected together by webs 25 26 and rigidly connected to the bottom rail, 10 while the members 21 may be independent of each other and separately connected to the body-strips 16^a 16^b of the top rail. As described in our prior patent, these body-strips of the top rail are separated from each other 15 at their lower side by a slot 27 of width sufficient to permit insertion of the pane and are connected together by a slide or cover 28, which forms the upper face of the rail. This cover being of sheet metal is flexible, so that 20 the body-strips, and with them the tongues 21, are movable toward and from each other, the distance between them being regulated by a clamping-screw 29, the shank of which passes through a hole in the web of one of the 25 tongues 21 and is threaded into the other tongue. When the parts are assembled, the clamping-screw 29 is adjusted to draw the body-strips together, and thereby the tongues 21 are caused to clamp tightly on opposite 30 sides of the internal ribs 15 in the cross-rail, thereby securely holding the cross-rail in frictional connection with the top rail. This construction, however, is not essential, as the projections 21 may be, if desired, joined integrally together in the same manner as are the tongues 24 by stiffening webs or flanges similar in all respects to the webs 25 26, which unite the members 24 and hold them at an invariable distance apart.
- 35 A window-sash constructed as hereinbefore described will have the maximum of strength and rigidity with a minimum weight, as is evident, besides being absolutely fire-proof.
- 40 The pulley 36, over which the sash-supporting weight chain or cord 37 passes, is secured in a novel manner. The pulley itself is pivoted at 38 to sheet-metal wings 39, between which it is located and the weight-chain is guided, and the wings being connected to and projecting outward from the sides of a face-plate 40. The plate 40 and wings 39 constitute a pulley-holding frame. Openings of sufficient width to admit insertion of 45 the pulleys and plates and of substantially the same size as said plates are made in the walls 41 of the side rails 22 of the window-frame in the sash-guides, and to these walls on the interior of the frame-rails are secured, 50 rigid metal plates 42, preferably castings. These plates are riveted to the walls 41 and extend over the pulley-receiving openings therein, being provided with registering openings 43, through which the pulleys and 55 wings 39 project, and having offset or de-
- pressed webs 44 to engage the ends of the face-plates 40. The latter are detachably secured to plates 42 by screws 45. Thus a structure of a sheet-metal window-frame to which sash-pulleys are detachably secured 70 and which has sufficient strength at the points of attachment thereof to support the weight of the sashes is secured.
- The weight-chain 37 is attached to the side rail of a sash by means of a hanger 48, having 75 an eye 49, to which the chain or cord is attached, and also having lateral projections 50 50, which form locking-bars. Preferably the hanger is constructed of wire bent so that its middle part forms the eye and its ends the 80 locking-bars, and the latter are offset from the plane of the eye, so as to extend into the interior of the rail, the eye and main portion of the hanger being contained in the channel between the window-frame and the strip 8 of 85 the rail. A keyhole-shaped opening 51 is formed in the strip 8 of the rail to permit detachment of the hanger therefrom, the detachment being effected by turning the hanger until the eye extends horizontally 90 and the locking-bars are vertical and then slipping one of the bars through the opening. After this has been done the other bar may be readily withdrawn.
- In the form of window illustrated in Figs. 95 10 to 14 there is substituted in place of the web 20 one or more plates or webs 52, extending longitudinally of the cross-rail 10 and also being preferably carried from one side to the other thereof in order to perform the stiffening function of the web 20. On the plates 52 are formed projecting fingers 53, which extend beyond the ends of the cross-rail and are adapted to project through slots 54 in the top and bottom rails on each side of the flanges 105 55 56, which are turned back to form the indented portions of these rails, which constitute the pane-receiving grooves of the rails. Cross-pieces 57 58 are placed in the upper and lower rails, respectively, extending from 110 side to side thereof in contact with the flanges 55 56, and the ends of the fingers are folded or lapped over the outer edges of the cross-pieces, thereby retaining them in the position above described and tying the top, bottom, 115 and cross rails together, thereby making a strong construction which holds the parts together, so that the panes of glass are firmly bound in place even when the window is so greatly heated that the rails become distorted 120 and sag. Without this construction the bottom rail of the sash when heated by a fire in the building wherein the window is placed would be caused by its own weight and that of the glass to sag down, separating the tops 125 of the panes from the upper rail, so that a stream of water striking them would knock them out of place, leaving the window unprotected. This objectionable result is prevented in our invention by reason of the fact 130

that the webs and cross-pieces, with the cross-rail, make a truss which holds the top and bottom rails at an invariable distance apart under all conditions, so that displacement of the panes is impossible. Obviously the webs may be secured to the cross-pieces in other ways than that shown, as by being riveted.

In the drawings there are shown two plates 52 placed side by side, their respective fingers being located on opposite sides of the cross-pieces 57; but it is obvious that, if desired, only one of such plates may be provided and that the cross-pieces may be securely held thereby. Also, instead of having webs 52 extending entirely across the rail 10 from side to side of the sash, the fingers 53 may be simply the ends of narrow strips extending the length of the cross-rail, but entirely separate from each other. With this 20 construction, however, less lateral stiffness is imparted to the cross-rail by these strips than is the case when they are connected and occupy the entire width of the rail.

The cross-pieces may have formed upon 25 their ends flanges 59 60 projecting perpendicularly from the body portions of the cross-pieces and in opposite directions, which flanges are adapted to bear against the side plates of the exterior rails of the sash and co-operate in giving stiffness to the sash.

We claim—

1. In a fireproof window, a sheet-metal sash having a cross-rail composed of two strips having the edges of one overlapped and folded together with the edges of the other, the strips being separated from each other at their intermediate portions and indented longitudinally to form pane-receiving grooves.

2. In a fireproof window, a sheet-metal sash having a cross-rail composed of two strips having the edges of one overlapped and folded together with the edges of the other, the strips being separated from each other at 45 their intermediate portions and indented longitudinally to form pane-receiving grooves and an internal stiffening member extended across said rail between the edges of said strips.

3. A cross-rail for a fireproof window-sash consisting of two strips of sheet metal arranged with the edges of one adjacent those of the other and interlocked and their intermediate portions separated, each of said strips being bent to provide grooves for receiving the window-panes, and a longitudinal stiffening-web located within the rail extending across the same and in engagement with the interlocked edges of said strips.

4. A fireproof window-sash having exterior rails, a hollow cross-rail, and connecting members held at their ends in the exterior rails and extending into and through said cross-rail.

5. In a fireproof window, a sheet-metal frame having a sash-guide provided with an opening, a rigid plate extending across such opening and secured to the frame, and a pulley-frame located in the opening and fastened to said plate.

6. In a fireproof window-frame, a sheet-metal side rail; a rigid metal plate secured to a wall of the side rail on the interior of the rail, the said wall and plate having registering openings, webs formed on said plate extending across the ends of said openings, and a pulley-frame located in the openings carrying a pulley projected into the interior of the rail and comprising in part a face-plate secured at its ends to said webs, and covering said openings.

7. In a fireproof window-frame, a sheet-metal side rail; a rigid metal plate secured to a wall of the side rail on the interior of the rail, the said wall and plate having registering openings, webs formed on said plate extending across the ends of said openings, a pulley-frame comprising a face-plate and laterally-extending pulley-supporting wings located in said openings, the face-plate being secured at its ends to said webs and covering the openings and the pulley-supporting wings extending through the openings into the interior of the side rail, and a pulley pivoted to said wings.

8. A fireproof window-sash having exterior rails of sheet metal with indented portions forming pane-receiving grooves, a hollow cross-rail, strips located within the cross-rail and extending longitudinally thereof, 100 projections extending from said strips into the interior of the adjacent exterior rail and bent over on their ends to form hooks, and a cross-piece extending transversely of said exterior rail in engagement with the indented portion thereof and engaged by said hooks.

9. A fireproof window-sash having exterior rails of sheet metal with indented portions forming pane-receiving grooves, a hollow cross-rail, transverse tie members located 110 in the exterior rails engaging the indented portions, a strip located within the cross-rail and extending across and longitudinally thereof, and projections extending from the ends of the strip into the interior of the exterior rails adjacent the ends of the cross-rail, on opposite sides of the indented portions of the exterior rails, and connected with the transverse tie members.

10. A fireproof window-sash having exterior rails of sheet metal with indented portions forming pane-receiving grooves, a hollow cross-rail, transverse tie members located in the exterior rails extending across the same in engagement with the indented portions thereof, and a plurality of strips extending longitudinally of the cross-rail in the interior thereof and having projecting portions

extending into the interior of the exterior rails on opposite sides of the tie members, the ends of said projecting portions being bent around the outer edges of the tie members.

5 11. In a window, a sash having a tubular side rail formed with an external channel on the side toward the adjacent rail of the window-frame, a sash-supporting cord or chain located in said channel, and a hanger having 10 a portion located in the channel engaged with the cord or chain and detachably connected to the sash-rail.

12. In a window, a sash having a tubular side rail formed with an external channel on 15 the side toward the adjacent rail of the window-frame, a sash-supporting cord or chain located in said channel, and a hanger having an eye located in the channel engaged with the cord or chain and a holding portion ex-

tending into the interior of and detachably 20 engaged with the sash-rail.

13. In a window, a sash having a tubular side rail and provided with an elongated slot in the portion adjacent the window-frame; and a hanger having an eye adapted to be 25 engaged with a sash-supporting weight chain or cord and having also an offset portion and a lateral retaining-bar adapted to extend through the sash-rail and engage the same in the interior thereof. 30

In testimony whereof we have affixed our signatures in presence of two witnesses.
